PILOT-WIRE PROTECTION FOR
TRANSMISSION LINES

Lester B. Le Vesconte, Irwin, Pa., assignor to
Westinghouse Electric & Manufacturing Com-
pany, East Pittsburgh, Pa., a corporation of
Pennsylvania

Application October 11, 1934, Serial No. 747,914

14 Claims. (Cl. 175—294)

This invention relates to a certain system of relay-protection for alternating-current transmission lines, known as pilot-wire protection, and it particularly relates to such a system in which 5 it is possible to use, at each end of the line-section being protected, current-differential relays which will operate only when the current-unbalance at the relay becomes more than a pre-determined percentage of the total current in 10 the transmission line.

Heretofore, in one pilot-wire system using current-balance relays, it has been necessary to utilize a relatively large artificial impedance load on the line-current transformers at each end of 15 the protected line-section, said load being considerably larger than the load imposed by the pilot-wire and the coils of the relays, so as to convert the current-transformer circuit into a voltage circuit, with a variable voltage impressed 20 over the pilot-wires, rather than a variable current. This imposes a very considerable extra load on the current-transformers, and is objectionable from other standpoints, as well. In another pilot-wire system heretofore proposed, it 25 has been necessary to utilize the differential current-relay at only one end of the pilot wire, thus requiring the trip-circuit to be carried over additional pilot wires to the other end.

An essential feature of my invention is the 30 provision of means for circulating over the pilot wire, or for transmitting through some other communicating channel, a current which is a predetermined composite function of the line-currents at both ends of the protected line- 35 section.

An important feature of my invention is that it permits the utilization of a percentage-unbalance relay at each end of the protected line-section, both of these relays responding to the 40 percentage or ratio represented by the difference between the line-currents at the two ends of the protected line-section divided by the line current. The denominator of this ratio may be represented either by the value of the line-current at only one end, or by the sum of the line-currents at the two ends of the protected line-section. 45

This type of relay is much more desirable than a relay which operates upon a predetermined 50 amount (rather than a predetermined percentage) of unbalance between the line-currents at the two ends. The reason for this is that it is necessary that the relay should not operate upon the occurrence of extremely heavy fault-currents 55 which flow all the way through the line, enter-

ing at one end and leaving at the other, so that the two line-currents at the opposite ends of the protected line-section are equal, and also in phase. Theoretically, the current-unbalance at the relay should be equivalent to the difference 5 of the currents in the two ends of the protected line-section, which would be zero in such a case, or in any case unless there should be a short-circuit at some intermediate point between the ends of the protected line-section. Actually, such 10 perfect balance is not possible, particularly under high-current conditions, which may cause the current transformers to approach saturation in different degrees, resulting in discrepancies in the current-transformer ratios at the two ends 15 of the protected line-section. The significance of this is that a current-unbalance relay which operates in response to a predetermined amount of unbalance may be operated when an extremely 20 large current flows through the protected line-section, whereas a current-differential relay which operates upon a predetermined percentage of unbalance will not be affected by the difference 25 in the characteristics of the current-transformers or by any other causes resulting in a comparatively very small current-unbalance as compared to the actual line-currents flowing at the moment. While my invention is not limited to the use of percentage-unbalance relays, it is, nevertheless, an important advantage of my invention 30 that it permits the use of such relays at both ends of the protected line-section.

With the foregoing and other objects in view, my invention consists in the circuits, systems, methods and apparatus hereinafter described and 35 claimed and illustrated in the accompanying drawing, wherein:

Figure 1 is an explanatory schematic view illustrating the general principles and operation of my invention; and

Figs. 2, 3 and 4 are similar views indicating 40 different forms of embodiment thereof.

Fig. 1 illustrates my invention as applied to a single-phase transmission line 5 having circuit breakers 6 and 7 at the respective ends 45 thereof. At each end there is provided a relay station at which is located a differential-current relay 8 and 9, respectively. These relays are shown as being of the current-differential type, each comprising an operating coil O and a 50 restraining coil R, said coils exerting torques in opposite directions on a movable element, in this case illustrated as a balanced beam 10, carrying a movable contact member 11. When the magnitude of the current in the operating coil 55

exceeds a predetermined percentage of the magnitude of the current in the restraining coil, the contact element 11 is closed and serves to energize the tripping circuit of the circuit breaker 6 or 7, as the case may be.

In the embodiment of my invention illustrated in Fig. 1, I provide a current-transformer 13 and 14, respectively, at each end of the protected line 5. The line-current is indicated at 1 and the secondary currents in the current-transformers 13 and 14 are indicated by I_1 and I_2 , respectively. The current I_1 of the current-transformer 13 is passed first through the restraining coil R and thence to an equalizer means 15 in the shape of the mid-tap of a current-transformer 15, wherein two branch circuits 16 and 17 are provided, each traversed by $\frac{1}{2} I_1$, as indicated by the arrows.

The end of the branch-circuit 16 is connected to two circuits, to wit, an operating-coil circuit 18, which contains the operating coil O, and a pilot-wire or communicating-channel circuit 19 which, in the form of embodiment shown in Fig. 1, is the actual pilot wire itself, said pilot wire extending between the two relaying stations at the opposite ends of the protected line 5. The impedance of the pilot wire is represented diagrammatically as being lumped at a single point and designated by the lumped impedance Z. The other branch-circuit 17 is also connected to two circuits, to wit, the other end of the aforementioned operating-coil circuit 18, and a dummy-impedance circuit 20 which contains a dummy impedance indicated by means of a current-transformer 21 and a lumped impedance 22, the resultant effect of which is equivalent to one-half of the impedance Z of the pilot-wire channel. The other ends of the dummy-impedance circuit 20 and of the pilot-wire circuit 19 are connected to the return-circuit 23 of the current-transformer 13.

Similar equipment is provided at the opposite end of the protected line 5 in Fig. 1, the connections being such that the currents circulated over the pilot-wire 19, or transmitted from one end of the line-section to the other by means of any equivalent communicating-channel, shall be equal to substantially $\frac{1}{4}(I_1+I_2)$.

It will be noted that the return-current I_1 , flowing in the conductor 23 back to the current-transformer 13, is divided between the dummy-impedance circuit 20 and the pilot-wire circuit 19, the latter comprising the first pilot-wire 24, the dummy-impedance circuit 20' at the opposite end of the line-section, the operating coil O of the differential current relay 9 at said opposite end, the second pilot-wire conductor 25 which is represented as carrying the lumped pilot-wire impedance Z, and the operating coil O of the differential current-relay 8 at the station containing the current-transformer 13. The pilot-wire current does not pass through the equalizer means 15 because said equalizer means has a very much higher impedance to through-currents than the impedance of the operating-coil circuit 18 which is shunted around it. This equalizer means permits the ready flow of current, only when equal and opposite currents are flowing in the two halves 16 and 17 thereof.

As compared to the impedance Z of the pilot-line, the impedances of the operating coils O may be regarded as negligible, or if not negligible, they may be considered as being lumped in the impedance represented at Z, and hence the impedance of the pilot-wire circuit, including the

dummy-impedance circuit 20' at the opposite end of the line-section, is $3/2Z$. It is, of course, apparent, therefore, that three-fourths of the relay current I_1 flows through the dummy impedance circuit 20 and one-fourth of it flows through 5 the pilot-channel.

The relay current I_2 originating at the other end of the protected line-section 5 is divided in a similar manner, as indicated by the arrows in Fig. 1, with the result that the pilot wire carries an operating current equal approximately to $\frac{1}{4}(I_1+I_2)$, whereas the two operating coils O of the two relays 8 and 9 at the opposite ends of the protected line-section are each traversed by currents $\pm\frac{1}{4}(I_1-I_2)$.

Fig. 2 illustrates the connections to the operating and restraining coils O and R of the relays for protecting a three-phase line-section 30 by means of a bank of star-connected current-transformers 31 and 32, respectively, at the opposite ends of the protected line-section. In this case, the pilot wires 34 are separate from the pilot-wire circuits 35, 35'; 36, 36'; 37, 37'; being connected by means of step-down current transformers 38 which make it possible to cause the currents circulated in the pilot wires 34 to be much smaller than the corresponding currents in the pilot-wire circuits, such as 35. In other respects, the operation of the three-phase system shown in Fig. 2 is as indicated in connection with Fig. 1, it being understood that three separate differential-current relays are utilized at each end of the protected line-section, so that if a predetermined differential current-unbalance is obtained in any one of the three phases, 35 suitable protective measures, such as the tripping of a circuit breaker (not shown in Fig. 2), or other protective means, may be set in operation.

Fig. 3 shows a modification of my three-phase protective scheme in which the current-transformers 31' are connected in delta, rather than being connected in star or Y formation. With this connection, the current-differential relays are designed to respond to phase-to-phase currents rather than phase-to-neutral currents. One advantage of this arrangement, as set forth in an application of W. A. Lewis, Serial No. 650,518, filed January 6, 1933, for Pilot-wire protection, is that the zero-sequence component of the line-currents in the protected line-section 30 are caused to circulate harmlessly in the delta-circuit of the current-transformers 31', and are kept out of the pilot wires 34, thereby avoiding certain trouble from inductive interference in the pilot wires 34 in the event of single-phase ground-faults.

The modification shown in Fig. 3 also includes a different type of equalizer means, consisting, in this case, of two small impedance devices 41 and 42, taking the place of the two branch-circuits 16 and 17 of the balance-coil current-transformer 15 in Fig. 1. In Fig. 3, by way of illustration, I have indicated the possibility of separating the restraining coil of each relay into two parts marked R1 and R2, respectively, and placing those two parts in the two branch-circuits 41 and 42, 65 respectively. It will be noted that the two branch-circuits 41 and 42 are connected together at one end, at what constitutes the middle point 43 of the equalizer device, and are connected at the other end by the relatively small impedance of the operating coil O. The impedances 41 and 42 of the equalizer device are made sufficiently large, relative to the impedance of the operating coil O, so as to exclude practically all of the pilot-wire current from the impedances 41 and 42, 75

and these impedances 41 and 42 are made substantially equal to each other so that the currents from the current-transformer 31' at the station in question are substantially equally divided.

5 In the embodiments of my invention shown in Figs. 1 to 3, it will be noted that the restraining coils R, or R1 and R2, as the case may be, are energized in accordance with the line-current at the station where the relay is located. This may 10 be taken as being sufficiently accurately responsive to the line-current. However, if it is desired to totalize the line-currents flowing at the opposite ends of the protected line-section, this may readily be done by placing the restraining 15 coil R in the pilot-wire circuit such as 35'', as indicated in Fig. 4, thus causing the restraining coil to be energized with a current which is proportional to the sum of the line-currents at the two ends of the protected line-section.

20 In the specification and claims, in referring to the sum or the difference of the line-currents at the two ends of the protected line-section, I refer to the normal current-flow, with current being considered positive at both ends of the line- 25 section, notwithstanding the fact that it flows into the line-section at one end and out of it at the second end. If the current reverses at the second end, as a result of an internal fault within the protected zone, the in-flowing current at that end 30 is then regarded as negative in value, and if it is equal to the in-flowing current at the first-mentioned end of the protected line-section, the resultant current flowing in the pilot wire, or otherwise transmitted by any suitable communicating channel, is equal to zero.

35 By my protective pilot-wire system, I impose only a small additional burden on each line-current transformer, as represented by the impedance $\frac{1}{2}Z$, which is small as compared to the 40 burden necessarily imposed by the pilot-wire and the operating and restraining coils of the relay. Moreover, by reason of the fact that I utilize percentage-differential relays, I provide a system which is not sensitive at all to slight maladjustments of the current-transformer ratios, or slight 45 maladjustments in the values of the dummy-circuit impedances or in the exactly equal division of the relay-currents in the two branch-circuits 16 and 17 or 41 and 42. At the same time, my relay 50 system is very sensitive to current-unbalance caused by the simultaneous in-flow of currents at the two ends of the protected line-section, so that positive tripping, or other fault-indication, may be obtained at both ends of the protected line-section, no matter where the fault is, and no matter 55 which end has the larger fault-current.

55 While I have illustrated my invention in several different forms of embodiment thereof, it will be understood that such illustration is not exhaustive 60 of the variations to which my invention is susceptible, without departing from the essential principles thereof. I desire, therefore, that the appended claims shall be accorded the broadest construction consistent with their language and 65 the prior art.

65 I claim as my invention:

1. Protective means for an alternating-current line having two distant relaying stations at opposite ends of a line-section thereof, means for 70 providing a communicating channel between said stations, line-current-responsive relay-current means at one relaying station for deriving a relaying current I_1 from said line, line-current-responsive relay-current means at the other relaying station for deriving a relaying current I_2 from said

line, said relaying currents I_1 and I_2 being substantially equal in phase and magnitude when no current is withdrawn from or supplied to the protected line-section at any point intermediate of its ends, equalizer means at the first relaying station 5 for providing two branch-circuits each traversed by substantially $\frac{1}{2}I_1$, equalizer means at the second relaying station for providing two branch-circuits each traversed by substantially $\frac{1}{2}I_2$, an operating-coil circuit and a communicating-channel circuit at each station, connected to the end of one of said branch-circuits, the other end of the operating-coil circuit at each station being connected to the end of the other branch circuit, a dummy-impedance means at each station, also 10 connected to the end of the last-mentioned branch-circuit, means including said communicating channel for linking together the communicating-channel circuits at the two ends of the protected line-section, the equalizer means at 15 each station being of such nature as to substantially exclude the flow therein of currents from the other end of the line-section, the dummy-impedance circuit at the first-mentioned station including such impedance as to cause sub- 20 stantially $\frac{3}{4}$ of the relay current I_1 to flow therein and to cause substantially $\frac{1}{4}$ of the relaying current I_1 to flow in the communicating-channel circuit at said station, the dummy-impedance circuit at the second-mentioned station including 25 such impedance as to cause substantially $\frac{3}{4}$ of the relaying current I_2 to flow therein and to cause substantially $\frac{1}{4}$ of the relaying current I_2 to flow in the communicating-channel circuit 30 at said station, whereby each of the communicating-channel circuits is traversed by a current of substantially $\frac{1}{4}(I_1+I_2)$, and each of the operating-coil circuits is traversed by a current of substantially $\pm\frac{1}{4}(I_1-I_2)$, and a differential-current relay at each station having an operating 35 coil energized in response to the operating-coil circuit at its station.

2. Protective means for an alternating-current line having two distant relaying stations at opposite ends of a line-section thereof, means for 40 providing a communicating channel between said stations, line-current-responsive relay-current means at each station for deriving relaying currents from said line, means for deriving, from 45 said relaying currents, and transmitting through said communicating channel, a current which is a substantially equal function of the relaying currents of both ends of the protected line-section, and a differential-current relay-means at each 50 end of the protected line-section, associated with the foregoing apparatus, each of said differential-current relay-means having an operating coil 55 connected to respond differentially to the line-currents at both ends of the protected line-section, and having a restraining coil connected to 60 be responsive to the magnitude of the line-current prevailing at the moment.

3. Protective means for an alternating-current line having two distant relaying stations at opposite ends of a line-section thereof, means for 65 providing a communicating channel between said stations, line-current-responsive relay-current means at each station for deriving relaying currents from said line, means for deriving, from 70 said relaying currents, and transmitting through said communicating channel, a current which is a substantially equal function of the relaying currents of both ends of the protected line-section, and a differential-current relay-means at each 75 end of the protected line-section, associated with

the foregoing apparatus, each of said differential-current relay-means having an operating coil connected to respond differentially to the line-currents at both ends of the protected line-section, and having a restraining coil connected to be responsive to the magnitude of the line-current at its own station.

portional to $\pm(I_2 - I_1)$, and a differential-current relay, at each station, provided with operating-coil means having said $\pm(I_2 - I_1)$ response, and provided with restraining-coil means connected to be responsive to the magnitude of the line-current at its own station. 5

4. Protective means for an alternating-current line having two distant relaying stations at opposite ends of a line-section thereof, means for providing a communicating channel between said stations, line-current-responsive relay-current means at each station for deriving relaying currents from said line, means for deriving, from 10 said relaying currents, and transmitting through said communicating channel, a current which is a substantially equal function of the relaying currents of both ends of the protected line-section, and a differential-current relay-means at each 15 end of the protected line-section, associated with the foregoing apparatus, each of said differential-current relay-means having an operating coil connected to respond differentially to the line-currents at both ends of the protected line-section, 20 and having a restraining coil connected to respond cumulatively to the line-currents at both 25 ends of the protected line-section.

5. Protective means for an alternating-current line having two distant relaying stations at opposite ends of a line-section thereof, means for providing a communicating channel between said stations, line-current-responsive relay-current means at each station for deriving relaying currents I_1 and I_2 , respectively, from opposite ends 30 of said protected line-section, said relaying currents I_1 and I_2 being substantially equal in phase and magnitude when no current is withdrawn from or supplied to the protected line-section at any point intermediate of its ends, means for 35 deriving, from said relaying currents, and transmitting through said communicating channel, a current proportional substantially to (I_1+I_2) , means at each end of said protected line-section, for responding to said transmitted (I_1+I_2) current and for responding substantially twice as 40 strongly to the local relaying current $(-I_1)$ or $(-I_2)$, as the case may be, so as to obtain a resultant response which is substantially proportional to $\pm(I_2-I_1)$, and a differential-current 45 relay, at each station, provided with operating-coil means having said $\pm(I_2-I_1)$ response, and provided with restraining-coil means connected to be responsive to the magnitude of the line-current prevailing at the moment.

55 6. Protective means for an alternating-current line having two distant relaying stations at opposite ends of a line-section thereof, means for providing a communicating channel between said stations, line-current-responsive relay-current means at each station for deriving relaying currents I_1 and I_2 , respectively, from opposite ends of said protected line-section, said relaying currents I_1 and I_2 being substantially equal in phase and magnitude when no current is withdrawn
60 from or supplied to the protected line-section at any point intermediate of its ends, means for deriving, from said relaying currents, and transmitting through said communicating channel, a current proportional substantially to (I_1+I_2) ,
65 from each end of said protected line-section, for responding to said transmitted (I_1+I_2) current and for responding substantially twice as strongly to the local relaying current $(-I_1)$ or $(-I_2)$, as the case may be, so as to obtain a
70 resultant response which is substantially pro-
75

7. Protective means for an alternating-current line having two distant relaying stations at opposite ends of a line-section thereof, means for providing a communicating channel between said stations, line-current-responsive relay-current means at each station for deriving relaying currents I_1 and I_2 , respectively, from opposite ends of said protected line-section, said relaying currents I_1 and I_2 being substantially equal in phase and magnitude when no current is withdrawn from or supplied to the protected line-section at any point intermediate of its ends, means for deriving, from said relaying currents, and transmitting through said communicating channel, a current proportional substantially to (I_1+I_2) , means at each end of said protected line-section, for responding to said transmitted (I_1+I_2) current and for responding substantially twice as strongly to the local relaying current $(-I_1)$ or $(-I_2)$, as the case may be, so as to obtain a resultant response which is substantially proportional to $\pm(I_2-I_1)$, and a differential-current relay, at each station, provided with operating-coil means having said $\pm(I_2-I_1)$ response, and provided with restraining-coil means responsive to the (I_1+I_2) current.

8. Protective means for an alternating-current line having two distant relaying stations at opposite ends of a line-section thereof, pilot-wire means between said stations, line-current-responsive relay-current means at one relaying station for deriving a relaying current I_1 from said line, line-current-responsive relay-current means at the other relaying station for deriving a relaying current I_2 from said line, said relaying currents I_1 and I_2 being substantially equal in phase and magnitude when no current is withdrawn from or supplied to the protected line-section at any point intermediate of its ends, equalizer means at the first relaying station for providing two branch-circuits each traversed by substantially $\frac{1}{2}I_1$, equalizer means at the second relaying station for providing two branch-circuits each traversed by substantially $\frac{1}{2}I_2$, an operating-coil circuit and a pilot-wire circuit at each station, connected to the end of one of said branch-circuits, the other end of the operating-coil circuit at each station being connected to the end of the other branch-circuit, a dummy-impedance means at each station, also connected to the end of the last-mentioned branch-circuit, means including said pilot-wire-means for linking together the pilot-wire circuits at the two ends of the protected line-section, the equalizer means at each station being of such nature as to substantially exclude the flow therein of currents from the other end of the line-section, the dummy-impedance circuit at the first-mentioned station including such impedance as to cause substantially $\frac{3}{4}$ of the relaying current I_1 to flow therein and to cause substantially $\frac{1}{4}$ of the relaying current I_1 to flow in the pilot wire-circuit at said station, the dummy-impedance circuit at the second-mentioned station including such impedance as to cause substantially $\frac{3}{4}$ of the relaying current I_2 to flow therein and to cause substantially $\frac{1}{4}$ of the relaying current I_2 to flow in the pilot-wire circuit at said station, whereby each of the pilot-wire circuits is traversed by a

current of substantially $\frac{1}{4}(I_1+I_2)$, and each of the operating-coil circuits is traversed by a current of substantially $\pm\frac{1}{4}(I_1-I_2)$, and a differential-current relay at each station having an operating coil energized in response to the operating-coil circuit at its station.

9. Protective means for an alternating-current line having two distant relaying stations at opposite ends of a line-section thereof, pilot-wire means between said stations, line-current-responsive relay-current means at each station for deriving relaying currents from said line, means for deriving, from said relaying currents, and transmitting through said pilot-wire means, a current which is a substantially equal function of the relaying currents of both ends of the protected line-section, and a differential-current relay-means at each end of the protected line-section, associated with the foregoing apparatus, each of said differential-current relay-means having an operating coil connected to respond differentially to the line-currents at both ends of the protected line-section, and having a restraining coil connected to be responsive to the magnitude of the line-current prevailing at the moment.

10. Protective means for an alternating-current line having two distant relaying stations at opposite ends of a line-section thereof, pilot-wire means between said stations, line-current-responsive relay-current means at each station for deriving relaying currents from said line, means for deriving, from said relaying currents, and transmitting through said pilot-wire means, a current which is a substantially equal function of the relaying currents of both ends of the protected line-section, and a differential-current relay-means at each end of the protected line-section, associated with the foregoing apparatus, each of said differential-current relay-means having an operating coil connected to respond differentially to the line-currents at both ends of the protected line-section, and having a restraining coil connected to be responsive to the magnitude of the line-current at its own station.

11. Protective means for an alternating-current line having two distant relaying stations at opposite ends of a line-section thereof, pilot-wire means between said stations, line-current-responsive relay-current means at each station for deriving relaying currents from said line, means for deriving, from said relaying currents, and transmitting through said pilot-wire means, a current which is a substantially equal function of the relaying currents of both ends of the protected line-section, and a differential-current relay-means at each end of the protected line-section, associated with the foregoing apparatus, each of said differential-current relay-means having an operating coil connected to respond differentially to the line-currents at both ends of the protected line-section, and having a restraining coil connected to respond cumulatively to the line-currents at both ends of the protected line-section.

12. Protective means for an alternating-current line having two distant relaying stations at opposite ends of a line-section thereof, pilot-wire means between said stations, line-current-responsive relay current means at each station for deriving relaying currents I_1 and I_2 , respectively, from opposite ends of said protected line-

section, said relaying currents I_1 and I_2 being substantially equal in phase and magnitude when no current is withdrawn from or supplied to the protected line-section at any point intermediate of its ends, means for deriving, from said relay-currents, and transmitting through said pilot-wire means, a current substantially proportional to (I_1+I_2) , means at each end of said protected line-section, for responding to said transmitted (I_1+I_2) current and for responding substantially twice as strongly to the local relaying current $(-I_1)$ or $(-I_2)$, as the case may be, so as to obtain a resultant response which is substantially proportional to $\pm(I_2-I_1)$, and a differential-current relay, at each station, provided with operating-coil means having said $\pm(I_2-I_1)$ response, and provided with restraining-coil means connected to be responsive to the magnitude of the line-current prevailing at the moment.

13. Protective means for an alternating-current line having two distant relaying stations at opposite ends of a line-section thereof, pilot-wire means between said stations, line-current-responsive relay-current means at each station for deriving relaying currents I_1 and I_2 , respectively, from opposite ends of said protected line-section, said relaying currents I_1 and I_2 being substantially equal in phase and magnitude when no current is withdrawn from or supplied to the protected line-section at any point intermediate of its ends, means for deriving, from said relay-currents, and transmitting through said pilot-wire means, a current substantially proportional to (I_1+I_2) , means at each end of said protected line-section, for responding to said transmitted (I_1+I_2) current and for responding substantially twice as strongly to the local relaying current $(-I_1)$ or $(-I_2)$, as the case may be, so as to obtain a resultant response which is substantially proportional to $\pm(I_2-I_1)$, and a differential-current relay, at each station, provided with operating-coil means having said $\pm(I_2-I_1)$ response, and provided with restraining-coil means connected to be responsive to the magnitude of the line-current at its own station.

14. Protective means for an alternating-current line having two distant relaying stations at opposite ends of a line-section thereof, pilot-wire means between said stations, line-current-responsive relay-current means at each station for deriving relaying currents I_1 and I_2 , respectively, from opposite ends of said protected line-section, said relaying currents I_1 and I_2 being substantially equal in phase and magnitude when no current is withdrawn from or supplied to the protected line-section at any point intermediate of its ends, means for deriving, from said relay-currents, and transmitting through said pilot-wire means, a current substantially proportional to (I_1+I_2) , means at each end of said protected line-section, for responding to said transmitted (I_1+I_2) current and for responding substantially twice as strongly to the local relaying current $(-I_1)$ or $(-I_2)$, as the case may be, so as to obtain a resultant response which is substantially proportional to $\pm(I_2-I_1)$, and a differential-current relay, at each station, provided with operating-coil means having said $\pm(I_2-I_1)$, response, and provided with restraining-coil means responsive to the (I_1+I_2) current.
